UNITED STATES PATENT OFFICE

168,397

ELECTRIC MOTOR

Richard W. Dochtermann, Fort Wayne, Ind., assignor to General Electric Company, a corporation of New York

Application March 6, 1952, Serial No. 18,804

Term of patent 14 years

(Cl. D26—5)

To all whom it may concern:

Be it known that I, Richard W. Dochtermann, a citizen of the United States, residing at Fort Wayne, State of Indiana, county of Allen, have invented a new, original, and ornamental Design for an Electric Motor, of which the following is a specification, reference being had to the accompanying drawing, forming a part thereof.

In the drawing:

Fig. 1 is a side elevational view of an electric motor showing my new design;

Fig. 2 is an end elevational view as seen from the right in Fig. 1.

The left end of the machine of Fig. 1 opposite the end shown in Fig. 2 is conventionally plain with no ornamental features.

I claim:

The ornamental design for an electric motor, as shown and described.

RICHARD W. DOCHTERMAN.
